UNITED STATES PATENT OFFICE.

PERCY B. CAMP, OF CHICAGO, ILLINOIS, ASSIGNOR TO UNIVERSAL DRAFT GEAR
ATTACHMENT CO., OF CHICAGO, ILLINOIS, A CORPORATION OF ILLINOIS.

CARRIER FOR DRAFT-GEAR YOKES.

1,208,911.

Specification of Letters Patent. Patented Dec. 19, 1916.

Application filed May 29, 1916. Serial No. 100,503.

To all whom it may concern:

Be it known that I, Percy B. Camp, a citizen of the United States, and resident of Chicago, county of Cook, and State of Illinois, have invented certain new and useful Improvements in Carriers for Draft-Gear Yokes, of which the following is a specification and which are illustrated in the accompanying drawings, forming a part

10 thereof.

The invention relates to a carrier for the yoke or coupler extension of a draft gear for railway cars; its object being to provide a support for the coupler extension upon 15 which it may freely move without wear; and it consists broadly of a strap or plate adapted for attachment to the draft sills or plates of a railway car and provided with a roller upon which the coupler extension may 20 ride, and more especially it consists of a structure such as is hereinafter described and as illustrated in the accompanying drawings, in which—

Figure 1 is a detail vertical transverse section of a pair of draft sills or plates, of the coupler extension and of the carrier; Fig. 2 is a plan view of the carrier detached; and Fig. 3 is a detail longitudinal view showing the yoke or coupler extension partially in section, a portion of the draft sill or plate in elevation, and an end view of the carrier, a part thereof being shown in section.

Portions of a pair of draft sills or draft plates are shown at 10, 11, and may be of any 35 desired form of construction, and there is shown at 12 a portion of a coupler extension here having the yoke form now in common use.

The carrier is shown as a casting 13, located below and attached to and connecting the draft sills or plates 10, 11. The casting may be secured to the draft sills or plates by any suitable means. As shown, the sills or plates are provided with outstanding 45 flanges 14, 15, at their lower edges, to which flanges the carrier is applied and secured by means of bolts, as 16, 17. Preferably the carrier is provided at its ends with gibbs 18, 19, engaging the outer margins of the flanges 50 14, 15. The carrier may also be provided with upstanding transverse flanges 20, 21, located between the draft sills or plates and

spaced apart to receive the coupler extension or yoke 12 and limit the lateral movement thereof.

55

The carrier is provided with a cage for containing a roller upon which the coupler extension may ride. As shown, this cage takes the form of a pocket 22, formed in the upper face of the carrier at its middle portion, within which the roller 23 is located. In order to avoid a useless weight of metal, this pocket is formed within a downward extension 24 of the body of the carrier. Preferably ribs, as 25, 26, cross the bottom of the recess 22 and form the ways upon which the roller 23 runs, the channels at each side of the ribs permitting any dust or cinders to accumulate therein. The floor of the recess may also be apertured, as shown at 27, to 70 permit the escape of dust and cinders.

60

The roller 23 is of sufficient diameter so that it projects slightly beyond the recess 22, in order that it may carry the coupler extension without permitting the latter to rub upon the upper surface of the casting 13. While endwise movement of the roller 23 is prevented by the walls of the recess, there may be provided a retaining and guiding rod 28 extending across the recess and fitting within an annular channel 29 in the roller. The length of the recess 22 is such that the roller may travel a sufficient distance to permit the maximum movement of the coupler extension.

75

While a desirable form of construction is herein shown and described, the details of the carrier may be varied therefrom without departing from the scope of the invention.

80

I claim as my invention—

85

1. A carrier for a coupler extension comprising, in combination, a member adapted for attachment to the draft irons of a car and having transverse ways, a roller running in the ways and adapted to support the coupler extension, such member being provided with upstanding transverse flanges forming lateral guides for the coupler extension.

90

2. A carrier for a coupler extension comprising, in combination, a member adapted for attachment to the draft irons of a car and having transverse ways, a roller having a circumferential channel and running in the ways and adapted to support the cou-

95

100

pler extension, and a guide rod fixed in the member and loosely fitting within the channel of the roller.

3. A carrier for a coupler extension comprising an integral casting adapted for attachment to the draft irons of a car and having a transversely extending pocket in

its upper face, a roller running within the pocket and adapted to support the coupler extension, and means for retaining the roller 10 in the pocket and for guiding it in its movements.

PERCY B. CAMP.
